UNITED STATES PATENT OFFICE.

GIDEON L. NOBLES AND WILLIAM F. NOBLES, OF LONE GROVE, TEXAS.

PLOW ATTACHMENT.

Application filed September 22, 1922. Serial No. 589,927.

To all whom it may concern:

Be it known that we, GIDEON L. NOBLES and WILLIAM F. NOBLES, citizens of the United States, residing at Lone Grove, in the county of Llano and State of Texas, have invented new and useful Improvements in Plow Attachments, of which the following is a specification.

This invention relates to farming implements, the general object of the invention being to provide means for attaching a shovel or the like to its standard.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a fragmentary view of a part of a cultivator showing our invention in use.

Figure 2 is a sectional view.

Figure 3 is a bottom plan view of the shovel.

Figure 4 is a cross sectional view through Figure 2.

In these views 1 indicates the standard of the implement and 2 the shovel or tooth thereof. In carrying out our invention we provide the standard with a wedge-shaped slot 3 and with an inclined notch 4 at each side of the slot. The standard is also provided with a hole 5 which communicates with the upper inclined part of the slot. The shovel or tooth is provided with a wedged part 6 for engaging the slot and with an inclined projection 7 on each side of the wedge for engaging the notches. The upper edge of the wedge is provided with

a semi-circular recess 8 which will register with the hole 5 when the parts are placed together. A pin 9 is adapted to be passed through the hole to engage the recess to lock the wedge in the slot. 45

From the above it will be seen that the shovel is firmly locked to the standard and that no movement can take place between the standard and shovel. In order to detach the shovel the pin must be knocked out and then the shovel can be moved away from the standard in order to pull the wedge and projections from the slot and recesses. All strain is taken by the inclined walls of the parts so that there is no danger of breaking the pin. 50

It is thought from the foregoing description that the advantages and novel features of the invention will be readily apparent. 55

We desire it to be understood that we may make changes in the construction and in the combination and arrangement of the several parts, provided that such changes fall within the scope of the appended claim. 60

What we claim is:—

In combination with a standard having a wedge-shaped slot therein and notches at the sides of the slot, the walls of the notches being inclined, said beam also having a hole passing through the same and in communication with the slot, a shovel having a wedge thereon for engaging the slot and inclined projections at the sides of the wedge for engaging the notches, said wedge having a recess therein which registers with the hole 80 when the wedge is in the slot and a pin passing through the hole and engaging the recess for holding the wedge in the slot and the projections in the notches. 75

In testimony whereof we affix our signatures.

GIDEON L. NOBLES.
WILLIAM F. NOBLES.
